UNITED STATES PATENT OFFICE.

CHARLES H. BRIGDEN, OF WALTHAM, MASSACHUSETTS, ASSIGNOR OF
TWO-THIRDS TO S. M. HAWES, JR., OF YONKERS, NEW YORK.

NIGHT-LATCH MECHANISM.

SPECIFICATION forming part of Letters Patent No. 562,373, dated June 23, 1896.

Application filed September 23, 1895. Serial No. 563,464. (No model.)

To all whom it may concern:

Be it known that I, CHARLES H. BRIGDEN, of Waltham, in the county of Middlesex and State of Massachusetts, have invented certain new and useful Improvements in Night-Latch Mechanism, of which the following is a specification.

This invention has relation to locks and latches of that class commonly known as "night-latches," in which the door-knob may be connected, at will, with or disconnected from the locking-bolt, so that the door may be opened from the outside by merely turning the knob, or else (when the knob and the bolt are disconnected) may be opened only by the use of a key.

The invention is designed for many objects, the principal of them being to provide a practically burglar-proof lock, or one that will baffle the ordinary thief; to simplify the parts of the lock so that they (the locks) may be manufactured cheaply and without the outlay of much capital; to reduce the number of operative parts by mounting the bolt-actuating mechanism in such way that it may be operated by the insertion of a key into the door-knob, and to provide simple means for connecting the knob-spindle with and disconnecting it from the bolt-actuating mechanism, which may be shifted from the inside of the door to render the use of a key unnecessary or necessary as the case may be.

Another object of my invention is to improve the construction and arrangement of the various parts of a lock, all as I shall hereinafter set forth.

To these ends my invention consists of a lock mechanism, one form of which I shall now proceed to describe with particularity. Reference is to be had to the annexed drawings, and to the letters marked thereon, forming a part of this specification, the same letters designating the same parts or features, as the case may be, wherever they occur.

Of the drawings, Figure 1 is an edge view of a portion of a door with my improved lock mechanism mounted thereon. Fig. 2 is a front view of the outer knob. Fig. 3 is a section on the line 3 3 of Fig. 1. Fig. 4 is a section on the line 4 4, Fig. 1. Fig. 5 is a central horizontal section on the line 5 5 of Fig. 4.

Fig. 6 is a central vertical section on the line 6 6 of Fig. 3, one of the knobs being broken off. Fig. 7 is an inner view of one of the roses and the parts mounted therein for connecting the knob with the spindle. Figs. 8 to 14, inclusive, show in detail some of the parts mounted in the knob. Fig. 15 is a side view of the key-actuated devices which are mounted in the knob, the parts of which are shown in detail in Figs. 8 to 14. Fig. 16 shows the key which may be employed. Fig. 17 shows the spindle detached. Fig. 18 is a perspective view of the lever which is operated from the inside of the door. Fig. 19 is a perspective view of one of the roses. Fig. 20 shows a plate which is secured to the rose.

In carrying out my invention, I aim to employ the simplest possible mechanism, and the fewest number of parts, in order that they may be contained within a small space, so as to allow of the key-actuated devices for connecting the knob with the spindle being placed within the knob itself and one of the roses.

The knob-spindle is indicated by *a*, and is secured to the shank *b'* of the inner knob *b* by a screw or otherwise, so as to turn with the knob as desired. *c* is the inner rose, having in this case a concentric annular ring *c'* to receive the end of the knob-shank *b'*.

The bolt or latch *d* is mounted in a tubular casing *e*, which is formed in two separable halves held together by a screw *e'*. The bolt or catch is bifurcated or forked so as to provide two arms *d'*, either of which may be engaged by the ends of a fin *f'* on a square apertured sleeve *f* through which the spindle *a* passes. The bolt is held outward by a spring *d''*. When the knob *b* is rotated, the spindle *a* in turning rotates the sleeve *f*, and causes the end of the fin *f'* to engage one of the arms *d'* and draw the bolt back.

The bolt-casing is provided with transverse grooves to receive tongues *g'*, extending inward from the arms *g''*, which are formed upon the outer rose *g*. When it is desired to secure the casing in a door, a cylindrical hole is bored into which the casing is placed. Then through a previously-bored transverse cylindrical aperture the arms of the rose *g* are thrust, so that the tongues *g'* will enter

the transverse grooves in the casing and hold it in place. Screws c^2 hold the rose c to the arms g^2 of the rose g , thus securing the outer rose in place from the inside so that no screws appear from the inside of the door.

The spindle is shaped as shown in Fig. 17, and extends a short distance through the bolt-casing. It is formed on the end with a cylindrical portion a' and a circular flange a^2 , having a cut-out, recess, or slot a^3 , and is also provided with a socket a^4 , extending into the end thereof.

The outer knob h is normally disconnected from the knob-spindle a , but is adapted to be connected therewith by means of a key or by another device, all of which I shall now describe. The said outer knob is formed with a cylindrical aperture or socket extending through the shank h' nearly to the front face of the knob, in which I mount the key-actuated means for connecting the knob h with the spindle a .

i is a casting (shown in Figs. 9, 14, and 15) which is inserted in the socket in the knob h , and having a concentric pin i' formed therewith adapted to extend loosely out into the socket a^4 of the spindle a , so as to loosely connect said casting and spindle together. The casting or support i for the movable parts is secured in the knob by a pin h^2 passing therethrough, as shown in Fig. 6, so as to connect the two rigidly together.

j is a spring-held lever (see Figs. 11, 13, and 15) mounted on the casting i and adapted to have its end thrown down into the slot a^3 in the spindle a , so as to rigidly connect the casting and the spindle together, the lever lying normally, however, in such position that it is out of the slot. Then by providing means for operating the lever I am enabled to connect the spindle and knob h together at will. The key-actuated mechanism for accomplishing this is mounted on the casting. The latter has a cylindrical end i^2 , reduced at i^3 , the latter having two outwardly-projecting studs i^4 . The casting or support has also a central flat portion i^5 , bifurcated to form two arms i^6 .

k is a double-arm lever with a cylindrical end bar k' resting in a socket i^7 in one side of the casting, one arm of said lever k having an inwardly and forwardly projecting finger k^2 , the end of the said arm lying between the edges of the arms i^6 . The lever j is fulcrumed on the cylindrical end bar k' , and has two studs j^2 j^3 lying in sockets in the two arms of lever k . By inserting a key l , such as shown in Fig. 16, in the keyhole h^3 in the knob h and turning it so that the ward l' lifts the end of one of the arms k' , the lever k will lift the outer end of lever j and throw the end j' down into the slot a^3 in the spindle. I provide means, however, for locking the lever k against movement, except when a certain key is used. The means consists of a two-armed lever m , having a cylindrical end bar m' lying in a socket i^8 in the casting opposite the socket i^7 .

One of the arms of the lever has a projection m^2 , with a socket m^3 , into which the finger k^2 on lever k projects, so as to lock the finger k^2 and lever k from movement until lever m is rocked on its fulcrum to move the projection m^2 away from the said finger. The ends of the arms of the lever m project into the space between the arms i^6 of the casting, so that they may be swung down by wards l^2 on the key. The two levers k and m are also provided with sockets k^3 and m^4 to receive the ends of a curved flat spring m^5 , which holds them together. The arms i^6 of the casting are also provided with wards i^9 to increase the difficulty of fitting a key to the lock. The key is provided with a pin l^3 , to which the duplicate wards are secured, so that when it is inserted the proper distance in the keyhole and rotated ward l^2 will first rock lever m so as to allow the lever k to be rocked when the ward l' presses on the end of the arms thereof.

i^{10} are stops between the levers k and m to prevent the spring from drawing them too close together. To insure that the lever j shall be returned to its normal position when released, I insert under it a spring j^3 . (Shown in Fig. 11 and in dotted lines in Fig. 5.)

It will be seen that when the levers are put in place in the casting and support, they are held there when they are all placed in the hollow knob.

In order to retain the knob in place in the rose g , I form the latter with an inwardly-projecting flange g^3 , having two recesses g^4 , corresponding to the studs i^4 on the cylindrical part of the casting which projects inwardly from the shank h' . When it is desired to secure the knob in place, the end of the pin i' is placed in the socket a^3 in the end of the spindle and the studs i^4 are thrust through the recesses g^4 . Then the knob and casting are turned for a quarter of a revolution until the lever j slips up into one of the recesses g^4 , thus locking the knob against rotation relatively to the rose g until the lever j is rocked down by means of the key and the key-actuated mechanism above set forth. The knob is therefore not only locked to the door or rose by the engagement of the stud i' with the flange g^3 on the interior of the rose, but is normally locked against rotation by the engagement of the lever j with the walls of one of the recesses g^4 in the said flange g^3 . (See Fig. 7.) The rose is also cast with a web g^5 above the end of lever j , and a coiled spring g^6 is placed around the pin i' of the casting, and has a leg on each side of the lever j resting against the web g^5 , so that after the lever j is depressed and the casting and knob have been turned relatively to the rose, the spring will throw the lever, the casting, and the knob back to their proper normal positions.

In addition to the key-actuated mechanism for connecting the knob with the spindle I also provide means which may be operated from the inside of the door, so as to render the use of a key unnecessary.

n is a semicylindrical rock-shaft (see Fig. 18) lying in a socket in one of the rose-arms *g*², and having near its end a curved arm or lever *n'*, lying between the innermost end of lever *j* and the wall of the cylindrical portion of the rose. It has a slot in its outer end adapted to receive the end of a pin *o*, which is rectangular in cross-section, and which extends through the inner rose *c*, and which is provided with a thumb-lever *p*.

q is a plate (shown in detail in Fig. 20) secured by screws between the arms *g*² to the inner walls of the rose *g*. It is centrally apertured to receive the cylindrical end of the spindle, so as to support the latter and hold it in engagement with the pin on the end of the casting. It also holds the curved arm or lever in place, as it forms half the bearing for a cylindrical portion *n*³ of the rock-shaft *n*.

20 The lever or arm *m'* lies normally, as said, above the end of the innermost end of the lever *j*, so that by throwing outward the end *p'* of lever *p* the rock-shaft *n* is turned slightly by the pin *o* far enough to cause the curved arm *n'* to press the end of lever *j* down into the slot *a*⁸ in the spindle *a*. The parts retain this position by the frictional engagement of the lever *p* and the pin *o* with the rose *c*, until the end *p'* of lever *p* is moved 30 toward the shank of knob *b*.

It will be seen that at all times the knob-spindle is longitudinally stationary—that is to say, the outer knob is locked to the spindle without any longitudinal movement.

35 By the foregoing description it will be seen that I have provided a locking mechanism which is formed of but few simple parts, and yet which is well adapted for the uses for which it is intended. It is unnecessary to 40 form a mortise in the door in which to place the lock, two cylindrical apertures, which may be formed by an ordinary boring-tool, being all that is required. The key-actuated mechanism for connecting the spindle and the outer 45 knob is all mounted in the knob, so that the key may be inserted in a hole therein, while until the knob is connected to the spindle it is locked against movement.

While I have shown and described one form 50 of my invention, in a lock mechanism which seems the best now known to me, yet I do not wish to be understood as limiting myself in any way to the details, as many changes could be made in the lock without departing from 55 the spirit and scope of my invention.

Having thus explained the nature of the invention and described a way of construct-

ing and using the same, though without attempting to set forth all of the forms in which it may be made or all of the modes of its use, 60 it is declared that what is claimed is—

1. A lock or latch mechanism comprising in its construction, an inner knob, a bolt or latch spindle secured thereto, an outer revolvable knob loosely connected to said spindle 65 but normally locked against movement to the door, and key-actuated means mounted in the last said knob for releasing it from engagement with the door and connecting it fixedly with the spindle, substantially as set forth. 70

2. A lock or latch mechanism, comprising in its construction, a spindle, a bolt or latch, a knob swiveled to said spindle, a removable support also swiveled to the spindle and rigid with said knob, a lever mounted on said support, and a key-actuated means for causing said lever to engage said spindle, said lever and said key-actuated means being mounted on said support whereby they may be withdrawn from the knob therewith, substantially 75 as and for the purposes set forth.

3. A lock or latch mechanism, comprising in its construction, a bolt or latch, a spindle, a knob, a support swiveled to the spindle and rigidly secured in the knob, a lever on said support for connecting the knob and the spindle, a key-actuated lever for operating the first said lever and means for locking the key-actuated lever, substantially as set forth. 85

4. A lock or latch mechanism comprising 90 in its construction, a spindle, a hollow knob, a rose, a lever, and key-actuated means mounted in the knob, for locking and unlocking the lever to and from the rose and to and from the spindle, substantially as set forth. 95

5. A night-latch mechanism comprising in its construction, a spindle, an inner knob rigid therewith, and outer hollow knob swiveled thereto, a lever connected to said outer knob and adapted to engage said spindle, key-actuated means in said knob for operating said lever, and a hand-actuated rotary rod extending from the inside of the door and having an arm for operating said lever, to render the use of the key unnecessary. 100 105

In testimony whereof I have signed my name to this specification, in the presence of two subscribing witnesses, this 14th day of August, A. D. 1895.

CHARLES H. BRIGDEN.
